A. C. Barstow.

Des. 1830

A. C. Barstow, of Providence, Rhode Island.
Letters Patent, No 1830-Dated Oct 18 1868
Design for a Caldron.

The schedule referred to in these Letters Patent and making part of the same.

To all whom it may concern:

Be it known that G. A. C. Barstow, of Providence, in the County of Providence and State of Rhode Island, have invented or produced a new and original design for a portable caldron; and I do hereby declare that the said new design is fully described and represented in the following specification and accompanying drawings to which reference is hereinafter made.

The figure of the accompanying plate of drawings represents my new design, being a perspective view of a portable caldron designed according to my invention.

The general form of my caldron is cylindrical or slightly tapering towards the lower side. The upper end is contracted by means of an ornamented moulding, the sides are ornamented by beads forming quadrangles whose corners are rounded in. The caldron proper is mounted on a fire chamber by means of a level connection also ornamented in front on either side of

Dec. 1830

a hinged door with projecting beads gracefully curved inwards as they approach the fire box. The latter has its corners rounded off and the sides ornamented with concentric beads: a moulded ash plate is in front and a moulded base runs around the bottom of the fire box.

Having thus described my improved design I claim the form and configuration of a portable cauldron, as herein shown and described, in combination with the described moulding and beads ornamenting the same.

For testimony whereof I have hereunto signed my name before two subscribing witnesses:
